WARD B. STORY, OF BROOKLYN, NEW YORK, ASSIGNOR TO WARD B. STORY COMPANY, INC., OF NEW YORK, N. Y., A CORPORATION OF NEW YORK.

ADJUSTABLE CAM.

1,210,559.

Specification of Letters Patent. Patented Jan. 2, 1917.

Application filed October 30, 1912. Serial No. 728,578.

To all whom it may concern:

Be it known that I, WARD B. STORY, a citizen of the United States, residing in the borough of Brooklyn, county of Kings, city and State of New York, have invented a certain new and useful Adjustable Cam, of which the following is a specification.

The objects I have in view are to secure the proper feed of the ink to the roller, irrespective of the consistency of the ink; to regulate the feed of ink, and to adjust such feeding while the press is in operation and without stopping it; to utilize the rolling effect of the supply roller to the utmost; to simplify the construction and make it sure and certain in operation; to compensate for the changed diameter of the supply roller, due to shrinkage thereof; to provide for gradually reducing the supply of ink to the press as the latter approaches the end of a run; to provide for arresting the feed of ink when the press is backed up for "making ready"; and to provide a positive feed for the ink, and avoid the use of ratchets and other intermittently operating mechanism. These and further objects will more fully appear from the following specification and accompanying drawings, considered together or separately.

In the drawings: Figure 1 is a sectional view on the line 1—1 of Fig. 2; Fig. 2 is a side elevation of an apparatus embodying my invention; Fig. 3 is a sectional view on the line 3—3 of Fig. 2; and Fig. 4 is a sectional view of the reservoir showing the supply roller and the supports therefor in elevation.

In all of the views, like parts are designated by the same reference characters.

In the embodiment chosen for illustration, the various instrumentalities for performing the functions of the invention are carried within or supported by the frame 1, of the apparatus. This frame supports the ink reservoir 2, which has a flexible bottom 3, and adjustable means 4 therefor. Any suitable form of flexible bottom and adjustable means may be employed, but I have illustrated in Fig. 4, the preferable means and devices which are shown and described

in my co-pending application for patent, filed October 1, 1912, Serial No. 723,318.

The fountain roller 5 is mounted on a shaft 6, in suitable bearings in the frame 1. It carries a crank 7, on one extremity. A 55 worm gear 8, is loosely mounted on the shaft 6. It is secured to the crank 7 by means of a screw bolt 9. By backing the screw bolt out of the worm gear, and attaching a crank (not shown) to one end of the 60 shaft, so that it will engage with the projecting part of the bolt, the fountain roller may be rotated by hand, when the supply of ink is introduced in the fountain. The worm gear 8 is engaged by a worm 10, which 65 is mounted on a worm shaft 11. This shaft has a bevel gear 12, at its lower end. This worm shaft 11 is mounted in bearings 13, in the frame 1. A cam shaft 14, is provided with a bevel gear 15, which engages with 70 the bevel gear 12. This cam shaft is provided with a drive gear 16. A drive shaft 17, is mounted in suitable bearings in the frame 1, and is provided with a drive gear 18, and clutch 19. This clutch may be of 75 any suitable type,—that illustrated in Fig. 1 being a jaw clutch of usual design. This form of clutch, connecting the drive gear 18 to the drive shaft 17, permits the shaft 17 to rotate the drive gear 18, when it turns 80 in one direction, but the dogs of the clutch slide by one another when the shaft is turned in the opposite direction. The elements of the clutch are held in engagement by means of a spring 19^a. The purpose of this clutch 85 is to prevent rotation of the cam shaft, and, through the gearing described, the fountain roller, when the press is backed up for "making ready." Without this clutch, the fountain roller would be rotated in the opposite direction, to the ordinary feed, and ink would be deposited upon the floor. 90

A supply roller 20 is carried upon a shaft 21, mounted in suitable bearings 22. These bearings comprise boxes, which are hinged 95 as shown, secured by screws so that the shaft may be lifted out in the usual manner. The supply roller is mounted upon arms 23, supported upon a shaft 24. In Fig. 3, which shows these arms, only one is illustrated, but 100

it is understood that a similar arm is to be placed on the other side of the frame, to hold the other end of the shaft 21. An ink roller 25, is carried upon an ink carriage 26, in suitable position to be engaged by the supply roller. The ink carriage engages a type cylinder 27, in the usual manner. For the purpose of elevating the supply roller, a rod 28 is provided, having a collar 29 thereon. 10 A spring 30, surrounds the rod and engages with the collar. One end of the rod is connected to the arm 23. The rod is mounted upon a support 31, through which it may slide and have the necessary amount of lateral movement to accommodate the change in the angle of the rod, due to the movement of the arm 23. The upper end of the spring 30 also engages with the support 31. The expansion of the spring exerts stress upon 15 the arm 23, and tends to normally elevate the supply roller.

For the purpose of depressing the supply roller to cause it to engage with the ink roller, a pitman 32, is provided. This pitman is secured to the arm 23 by means of a bolt 33. The bolt is mounted in a slot in the arm, and is best shown in Figs. 2 and 4, so that the position of the bolt may be adjusted to accommodate changes in diameter 20 of the supply roller due to shrinkage of the latter, to always insure proper engagement of the latter with the ink roller. The pitman 32 has a fork 34 at its lower end. It also is provided with rollers, 35 and 36, 25 which engage with a fixed cam 37, and movable cam 38, respectively. The fixed cam, which is secured fixedly upon the cam shaft, is of such a shape that the engagement of the roller 35 with it will elevate the pitman and 30 depress the supply roller and cause it to engage with the ink roller through the minimum proportion of time, during which the apparatus is designed to operate. The movable cam 38 is adapted to be rotated, in relation to the fixed cam, so that the period of 35 time in which the supply roller will be engaged with the ink roller will be increased up to the maximum proportion. The rollers 35 and 36 engage these two cams. It 40 will be understood that both rollers being carried upon the pitman, the latter will be elevated when either of the rollers 35 or 36 is in engagement with the high part of either of the cams 37 or 38. It will also 45 be understood that if the movable cam is rotated in relation to the fixed cam, the extent of the high part of the two cams, together, will be increased, and hence the supply roller will be depressed through a longer 50 interval of time in relation to the rotation of the other rollers.

The means for changing the angular position of the movable cam is as follows: The cam is connected to the first differential 39. 60 This differential is mounted upon the cam

shaft 14. The first differential consists of a bevel gear 40, directly connected to the movable cam; a center member 41, rotatably mounted upon the cam shaft; and a bevel gear 42, also rotatably mounted upon the cam shaft. The center member of the differential is in the usual form, and carries one or more bevel pinions which engage with the bevel gears 40 and 42. The second differential 43, consists of a bevel gear 44, attached to and rotating the bevel gear 42. It also comprises a center member 45, and a bevel gear 46. This center member is of the same character as the preceding center member. The bevel gear 46 is secured to the shaft 43 so that it will be rotated by the latter. The center member 45, is prevented from rotating by means of the support 47, (see Fig. 3). For the purpose of changing the angular position of the center member 41, it is provided with a lever 48. This lever has a nut 49, (see Fig. 2). This nut engages with a rod 50, having screw threads 51, where it passes through the nut. The rod is carried upon a support 52. It is rotated by a hand wheel 53. It is apparent that by rotating the hand wheel 53, the free end of the lever 48 will be raised or lowered, thus changing the angular position of the center member 41. The movable cam is rotated on the shaft 14, when the center member is moved, through the agency of the bevel gears 46 and center member 45 and bevel gear 44. It is apparent that if the bevel gears 44 and 46 are the same size, the center member will be prevented from rotating by means of the support 47, and the bevel gear 44 will turn at the same rate of speed as the shaft 14, but in the opposite direction. The bevel gear 44 rotates the bevel gear 42, which rotates the bevel pinions which are in the center member 41. These bevel pinions will rotate the bevel gear 40 in the direction opposite from which the bevel gear 42 rotates. In other words,—it will rotate it in the same 110 direction as the shaft 14. Assuming that the lever 48 is not moved, it is apparent that the bevel gear 40 and movable cam rotate at the same rate of speed as the shaft 14, and in the same direction. It is, therefore, apparent that if the free end of the lever 48 be raised or lowered to change the angular position of the center member, the position of the first differential will be changed, which will result in shifting the 115 angular position of the movable cam. The purpose of having two differentials is to insure that the two cams 37 and 38 will rotate in the same direction, so that the wear upon the cam gear and shaft will be reduced. It 120 is of course understood that the second differential can be omitted if it is so desired, in which event, the cams will rotate in opposite directions.

It will be apparent, from the foregoing 125

description, that I avoid the usual pawl and ratchet mechanism for rotating the fountain roller at varying speeds, as has been heretofore customary. By utilizing the 5 worm gear described, the fountain roller is rotated at constant speed. The consistency of the ink will determine the thickness or thinness of the film. The amount of ink which is supplied to the ink roller will be 10 varied by the relative period of time in which the supply roller is in contact with the fountain roller, or out of contact therewith. By utilizing the adjustable bottom of the receptacle, the thickness of the film of 15 ink may be varied in accordance with the consistency of the ink, irrespective of the feed.

In operating the device, it is apparent that when the press is getting near to the end of 20 a run, the operator, by adjusting the position of the hand wheel 53, can vary the relative period of time during which the supply roller is in contact with the fountain roller, so that when the run is finished, there will 25 be no surplus ink upon the rollers of the ink carriage.

The great advantage of the device is that the thickness of the ink film on the fountain roller is determined by the consistency of 30 the ink, and the supply is regulated entirely by the interval of time in which the supply roller dwells on the fountain roller. All the time that the supply roller is not in contact with the fountain roller is utilized in rolling 35 the ink on the ink roller.

In accordance with the provisions of the patent statutes, I have described the principle of my invention, together with the apparatus which I now consider to represent 40 the best embodiment thereof; but I desire to have it understood that the apparatus shown is merely illustrative and that the invention can be carried out in other ways.

Having now described my invention, what 45 I claim as new, and desire to secure by Letters Patent, is:—

1. An adjustable cam comprising a fixed cam member, and a movable cam member, an immovable element, and a screw carried 50 by the element for adjusting the members to change the relative angles of the members.

2. An adjustable cam comprising a fixed cam member and a movable cam member, an immovable element, a device associated with 55 the movable member, a nut carried by the device, and a screw supported on the element and engaging the nut whereby the relative angle of the members may be changed.

60 3. An adjustable cam comprising a fixed cam member and a movable cam member, an object moved in one direction by the cam, independent means for moving the object in the opposite direction, means for adjusting 65 the initial position of the object relatively

to the cam, an immovable element, and a screw carried by the element for adjusting the members to change the relative angles of the members.

4. An adjustable cam comprising, a fixed 70 cam member and a movable cam member, an object moved in one direction by the cam, independent means for moving the object in the opposite direction, means for adjusting the initial position of the object 75 relatively to the cam, an immovable element, a device associated with the movable member, a nut carried by the device, and a screw supported on the element and engaging the nut whereby the relative angle of the members 80 may be changed.

5. An adjustable cam comprising a fixed cam member and a movable cam member, an object moved in one direction by the cam, a spring for moving the object in the opposite 85 direction, means for adjusting the initial position of the object relatively to the cam, an immovable element, and means stationary on the element for changing the relative angles of the members, said means 90 being operable irrespective of the positions of the members.

6. An adjustable cam comprising a fixed cam member and a movable cam member, an object moved in one direction by the cam, a 95 spring for moving the object in the opposite direction, means for adjusting the initial position of the object relatively to the cam, an immovable element, a differential gear connected to the movable member, said differential gear including a center member, and means stationary on the element for moving the center member. 100

7. An adjustable cam comprising a fixed cam member and a movable cam member, 105 an object moved in one direction by the cam, a spring for moving the object in the opposite direction, means for adjusting the initial position of the object relatively to the cam, an immovable element, a differential gear, 110 said differential gear including a center member, means for moving the center member, a second gear having an immovable center member whereby the two cam members will rotate in the same direction. 115

8. An adjustable cam comprising a fixed cam member and a movable cam member, an object moved in one direction by the cam, a spring for moving the object in the opposite 120 direction, means for adjusting the initial position of the object relatively to the cam, an immovable element, and a screw carried by the element for adjusting the members to change the relative angles of the members. 125

9. An adjustable cam comprising a fixed cam member and a movable cam member, an object moved in one direction by the cam, a spring for moving the object in the opposite 130 direction, means for adjusting the ini-

tial position of the object relatively to the cam, an immovable element, a device associated with the movable member, a nut carried by the device, and a screw supported on the element and engaging the nut whereby the relative angle of the members may be changed.

This specification signed and witnessed this 26th day of October, 1912.
